CLAIM

The ornamental design for a container with lid, as shown and described.

DESCRIPTION

FIG. 1 is a top, front, right-side, perspective view of a container with lid;

FIG. 2 is a bottom, front, right-side, perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a top, front, right-side, exploded perspective view of the container with lid, with the strap shown in broken line, as unclaimed environmental matter;

FIG. 10 is a top, front, right-side, perspective view of the container with lid, with the strap shown in broken line, as unclaimed environmental matter; and,

FIG. 11 is a top front, right-side, perspective view of the container with lid, with the strap shown in broken line, as unclaimed environmental matter.

In the drawings, the broken lines are for the purpose of illustrating environment only and form no part of the claimed design.

1 Claim, 8 Drawing Sheets
